FACSIMILE-PRODUCING SYSTEM.

Application filed December 12, 1925. Serial No. 75,034.

The invention concerns a method and means for reproducing impressions of graphical or visual records and has for its principal object to simplify the present 5 methods of reproducing such records.

The invention more particularly concerns a method and means for reproducing impressions of graphical or visual records by the so called process engraving systems and 10 has for a particular object the elimination of the usual photographic step in such processes.

A further object of the invention is to provide for reproducing impressions of graphical or visual records by transferring such 15 records into electric currents and recording the currents on a medium which in itself may be used for reproducing impressions.

Still another object of the invention is to 20 provide for reproducing impressions of graphical or visual records by transferring such records into electric currents and recording the currents on metal which may thereafter be treated to form a printing 25 plate or cut from which prints may be made.

Still another object of the invention is to provide for reproducing impressions of graphical or visual records by transferring such 30 records into electric currents and recording the currents on metal by means of an acid resisting writing material so that thereafter the original metal may be treated to form a cut from which additional impressions may be made.

The invention finds its most useful application as a substitute for the well known zinc etching and half tone engraving processes in which line drawings, photographs or other graphical records are first photographed and then transferred to a metal plate by a tedious and expensive series of steps requiring the services of a large number of highly skilled workmen and entailing considerable delay in obtaining the required printing plate or cut. It is proposed to form an image of the record to be reproduced directly on the metal plate by electrical means in such form as to admit of etching without further treatment, thus eliminating the photographic step with its associated processes and dispensing with the services of the skilled workmen at present necessary in actually preparing the plate for the etching process. The etching process proper may be carried out in the usual manner after the impression has been electrically transferred to the plate.

The advantages of the system may be most clearly understood by a brief consideration of the zinc etching and half tone processes as they are carried out at present.

The zinc etching process consists in photographing the picture to be reproduced by the wet plate process, in which an albuminized plate is covered with collodion and placed in a bath of light sensitive silver solution. A photographic exposure of the picture is made using this sensitized plate. The plate is then developed and cyanide of potassium solution poured over it to dissolve all portions of the sensitizing solution not acted upon by light, leaving the picture in the shape of a negative on the collodion covering. The image is then intensified by placing it in a bleaching bath of copper, after which it is washed and the plate treated with a solution of iodine to build up the body of the picture and with cyanide solution to remove the superfluous material on the plate. After drying, the plate is flowed with rubber dissolved in gasoline, dried and flowed with leather collodion. The negative is then cut with a sharp knife to the proper dimensions and placed in acetic acid to dissolve the albumen. It is thereafter stripped bodily from the glass plate and turned over on to another glass plate. This forms what is called the "flat", in reality a negative from which the positive is to be formed on the printing plate. A sheet of zinc is now sensitized and placed with its sensitized surface against the negative which is subjected to a strong light to form a positive on the sensitized zinc surface. The flat is removed from the plate and the latter is washed to remove the unexposed parts of its light-sensitive coating, leaving only the lines of the desired positive on the plate. The plate is then inked and covered with a topping powder which clings to the ink lines but not to the other portions of the plate. The plate is heated slightly to melt this powder which then forms an acid resisting surface conforming to the lines of the positive. The plate is then given several bites with acid, using dragon's blood between each bite to protect the crevices from the action of the acid which otherwise would tend to undercut the lines of the image. Finally the zinc plate is washed off with a lye solution.

and can be blocked into a printing frame to strike off impressions of the received picture.

Reproductions are also made by the half tone process which is somewhat similar to the zinc etching process but which makes use of copper plates instead of zinc. This is a higher grade of work and differs from the zinc etching process in that the picture is photographed through a screen which in effect gives a negative in the form of small black and white dots. From this point the process is substantially similar to the zinc etching process except that more care and different chemicals are necessary to adopt the process to the copper plate and to bring out the finer details.

According to the present improved process the picture to be reproduced is mounted on a carriage and a beam of light caused to shine on or through it and fall on a light sensitive cell. By relative movement of the light and picture the beam can be made to gradually pass over the entire picture and its intensity at any instant will be governed by the particular shade of the picture at the point through or on which the beam happens to be shining. The light sensitive cell can be made to control a source of electrical energy and, owing to the variations in intensity of the beam, can cause the source to give out pulses of energy variably spaced to correspond to the shading of the picture or a variable duration to correspond to the shading or a mixture of both. While I do not wish to be limited to such an adaptation I have found that the apparatus described in my copending application 695,175, filed February 26th, 1924 is very well suited to the present process. In that application a beam of light of variable intensity controls a light sensitive cell which in turn controls an apparatus giving rise to a series of variable spaced current pulses. These pulses are caused to intermittently energize a magnet operating a pen which records the pulses in ink on a sheet of paper moving in synchronism with the picture being duplicated. The pen therefore forms a replica of the original picture in the shape of variably spaced dots. Under the present process a metal plate of either copper or zinc may be substituted for the paper and the ink in the pen may be replaced by a suitable acid resisting writing fluid.

There are a number of substances which may be used as the acid resisting writing fluid such as, for example, a fine grade of Egyptian asphaltum, beeswax, carnauba wax and others but I prefer to use paraffin which presents the advantages of being easily procurable, easily reduced to and maintained in a liquid state, is non-drying on the pen, flows on to the metal instantly and dries quickly and sticks well to the

metal. It will be noted that all of these substances are solids at normal temperatures and must be melted and kept melted while the recording pen is in use. No particular disadvantage results from this feature as it is quite practical to heat the pen and keep it hot enough to melt the writing material and maintain it in a liquid state.

When the picture is transferred in this fashion to the metal plate the latter can be removed from the machine and given the first acid bite without further treatment after which it can be dusted with dragon's blood and given as many additional bites as may be necessary. It will be noted then that the process of reproducing the impressions is considerably simplified in that it dispenses with all the highly specialized treatments preceding the first bite which are essential under the present process engraving methods.

The invention may be more clearly understood from the following detailed description which should be read in connection with the accompanying drawings in which the same reference numerals have been retained throughout the several views and in which:

Fig. 1 represents schematically an elevation of the picture recording device.

Fig. 2 represents a sectional view of the device shown in Fig. 1.

Fig. 3 is a diagrammatic representation of a method for receiving and recording transmitted pictures and

Fig. 4 is a diagrammatic representation of an arrangement of the electrical circuits for transferring the picture to the metal plate.

Referring first to Fig. 3, which indicates diagrammatically the method of recording pictures according to my corresponding application No. 695,175, filed February 26th, 1924, the line OZ represents the time axis. The row of dots C represents the spacing of dots for the different shades in the picture. The curve B represents the current amplitude in the pen operating magnet during the recording of the picture and the band A represents the shades in the picture. In this diagram the space OV represents black in the picture. Here the dots are very close together and give the effect of black. The space VW represents dark gray and the dots here are spaced further apart to allow a larger percentage of white in the picture. Spaces WX and XY represent light medium gray and light gray, respectively, which effects are obtained by spacing the dots further apart, while the space YZ represents white, which obviously is represented by an absence of operating current in the operating magnet. In this method the variably spaced dots are transmitted from the sending device to correspond to the different shades in the picture and are impressed on

the record at the receiving device, the different shades of the picture being reproduced by the receiving device by means of the variably spaced dots. It is obvious, however, that the present system is not limited to pictures recorded in this manner but is applicable as well to all methods which use either dots or broken lines in combination for forming an image.

- 10 Referring now to Fig. 4 in which is shown by way of example a diagrammatic arrangement of a device for carrying out the invention, M designates a motor of any suitable type arranged to drive two cylinders 16 and 20, of which 20 may be called the transmitting cylinder and 16 the receiving cylinder. The cylinder 20 is transparent and arranged to have the picture to be reproduced supported on its cylindrical surface. Within 20 in the cylinder is mounted a source of light 21, in proximity to which is a condensing lens 22 for causing a small beam of light to be focused on a small area of the picture and shine therethrough. This beam of light will, 25 of course, have its intensity changed in accordance with the shading of the picture at the particular area through which it happens to be shining. After passing through the picture the modified beam is focused by 30 means of a second condensing lens 23 on a small opening in an opaque casing 24 containing a light sensitive cell 25 of a type well known in the art. The current passing through the light sensitive cell will therefore 35 be regulated by the intensity of the beam of light which in turn is controlled by the shading of the picture mounted on the cylinder 20. In addition to its rotative movement the cylinder 20 is given a longitudinal movement by a screw threaded shaft 40 or otherwise so that the beam of light progressively passes over each small portion of the picture and controls the energization of the light sensitive cell in accordance therewith.

The cylinder 16, likewise driven by the motor M, rotates at the same speed as the cylinder 20 and is given a longitudinal movement corresponding exactly with that of the cylinder 20. The cylinder 16 has on its surface a metal plate on which are recorded by means of the pen 12 markings corresponding to the picture carried by the cylinder 20 in a manner to be hereinafter described.

The apparatus for translating the variations of the beam of light shining through the picture into variations of electric current for operating the magnet of the pen 12 consists in addition to the light sensitive cell 25 of two electronic relays 29 and 30, a condenser 31 and a pair of relays 34 and 38. The light sensitive cell has its electrodes connected in circuit with a battery 26 and a relatively high resistance 27, one cell elec-

trode being connected to the negative pole of the battery and the other being connected to the terminal A of the resistance. The positive pole of the battery is connected to the terminal B of the resistance. The voltage across the points A and B will then be governed by the intensity of the beam of light falling upon the light sensitive cell. The relay 29 has its input circuit connected across the terminals A and B so that upon closure of its anode circuit its space current will be governed by this voltage and therefore by the intensity of the beam of light. The anode circuit of the relay 29 includes two parallel branches, one comprising the condenser 31 and the other including the contacts of the relay 34, a resistance 40, the coil 35 of relay 38 and a source of energy 36, the latter supplying the plate voltage for the relay 29. The input circuit of the electronic relay 30 is connected across the condenser 31 and contains a source of energy 32 for negatively biasing the grid thereof. The output circuit of this electronic relay includes the coil 33 of relay 34 and the source of energy 36 which likewise supplies the plate potential for this relay. The relay 38 controls the circuit of the operating magnet 1 which contains a source of energy 37.

This apparatus is very similar to that shown in my copending application 695,173 with the exception that in the present case exact synchronism is obtained between the transmitting and receiving cylinders by driving them with the same motor. The operation of this device which is described briefly hereinafter is explained in detail in the said prior application. Briefly the operation may be explained as follows: Consider the relay 34 to be in its normal closed position and condenser 31 to be discharged. The tube 29 then gets plate voltage from the battery 36 and owing to the voltage drop across the points A and B, which will increase as the intensity of the beam of light shining through the picture increases, the grid of the tube 29 will be properly biased to cause a space current corresponding in value to the intensity of the beam to flow in the anode circuit of this tube thus charging the condenser 31. At this time also the relay 38 will be closed. The tube 30 has no space current flowing through it at this time owing to the negative bias on its grid resulting from the battery 32. As the charge on the condenser 31 increases, however, this negative bias is gradually diminished and when the charge on the condenser reaches a certain value the negative bias due to the battery 32 will be overcome and the grid of the tube 30 becomes positive and causes current flow in the anode circuit of this tube. This anode current flowing through the winding 33 opens the contacts of relay 34, disconnecting

110
115
120
125
130

the battery 36 from the anode of the tube 29 and deenergizing the coil 35 of relay 38 which thereupon opens the pen operating circuit. The condenser 31 now begins to discharge through the tube 29 and at a certain point in the discharge, the grid of the tube 30 again becomes negative due to the bias of the battery 32. The space current of this tube decreases and deenergizes the coil 33 whereupon the relay 34 closes its contacts, again applying voltage from the battery 36 to the anode of tube 29 and causing the closure of the relay 38 owing to the energization of its coil 35. The condenser 31 again begins to charge and the cycle is repeated. The closure of the relay 38 serves to energize the operating magnet of the pen 12 in a manner to be hereinafter described and the markings of the pen 12 follow the cycle of the operations just described. It will be noted that the frequency of this cycle of operation depends on the capacity of the condenser 31, the negative bias on the grid of tube 30, governed by the voltage of the battery 32, and the change in voltage across the points A and B. As the capacity of the condenser 31 and the voltage of the battery 32 are fixed, any change in the frequency of the cycles of operations will be governed by the changing voltage across the points A and B and this voltage as explained above is governed by the intensity of the beam of light falling from the light sensitive cell 25 which in turn is governed by the shading of the picture carried on the cylinder 20 at the particular point through which the beam of light happens to be passing. The pen 12 owing to the variable time spacing between closures of the relay 38 will record a series of dots variably spaced according to the shading of the picture.

It will be noted that in this system the shading of the picture is obtained by recording dots of the same size but variably spaced. It should be understood, however, that the system in its broader aspects is equally well adapted to reproducing pictures by dots variably spaced or dashes of variable length equally spaced or by a series of broken lines and dots or by a mixture of any of these. A system for reproducing pictures using dashes of variable length equally spaced for the darker shadings and dots variably spaced for the lighter shadings as disclosed in my prior copending application, Serial No. 726,235, filed July 16th, 1924, has been found to be very well adapted to the present system of engraving.

The operation of the pen in marking the metal plate in response to the closing of the control relay 38 can be best understood by referring to Figs. 1 and 2 of the drawing in which 1 represents the operating magnet connected as shown in Fig. 4 in circuit with the control magnet 38 and a source of energy 37.

The operating magnet 1 is energized whenever the control relay 38 is closed and attracts an armature 3 fixed on one end of a lever 4 pivoted at 5. On the other end of this lever is fixed the pen mechanism consisting of a hollow tube 10 bent into general U-shape and carrying at its end a pen 12. This pen is in the form of a metal strip bent into U-shape and having its free ends suitably shaped to form pen points. The stud 13 is provided for changing the distance between the pen tips to vary the size of the dots or lines formed by the pen. The pen is provided with an aperture at 14 which communicates with the interior of the tube 10 and a wick 11 is placed in the tube having one end extending into the aperture of the pen and the other end projecting a slight distance beyond the end of the tube. The action of the magnet 1 in response to current impulses tends to raise and lower the pen 12 to cause it to touch at intervals the plate 15. The plate 15 is mounted on the receiving cylinder 16 shown in Fig. 4 and moves in synchronism with the transmitting cylinder 20. The end of the tube 10 extends into a tank or receptacle 6 in which is placed the paraffin serving as the writing material. This receptacle has a partition 7 forming a hollow space 8 inside the tank in which is placed a heating coil 9. When current is sent through this heating coil, the paraffin is melted and the coil also serves to keep the tube 10 and the pen 12 heated sufficiently to maintain the paraffin in a liquid state. The paraffin owing to its creeping or capillary characteristics is drawn from the tank 6 into the pen 12 whereby a small amount of melted paraffin is constantly supplied to the latter. As the magnet 1 is energized by the current impulses resulting from the operation of control relay 38 the pen is intermittently applied to and removed from the plate 15 and every time it touches the latter a mark formed of paraffin is left thereon.

The dots made by the pen 12 in the present case are spaced to correspond to the shading of the picture on the transmitting cylinder and when the picture is finally transmitted, the plate 15 has recorded thereon in paraffin an accurate reproduction of the picture. As the paraffin protects the portions of the plate which it covers from the action of the etching acids the plate may be subjected without additional treatment to an acid bite to eat away the metal between the lines of the picture. After the first bite dragon's blood may be sprinkled on the plate and brushed off leaving only a small amount in the crevices which it is desired to protect from the acid of the next bite. The plate is then heated slightly to melt this small residue of dragon's blood and after cooling is given another bite. This process may be repeated until the de-

sired depth of cut is obtained, after which the paraffin may be removed by dissolving in ether or any other paraffin solvent and prints struck off from the plate by the usual printing methods.

The modification of the invention shown concerns an apparatus for reproducing pictures for the sole purpose of obtaining cuts or printing plates of them. In this case, the transmitting and receiving cylinders are located in the same room and can be driven as shown by a common motor to obtain synchronism. The leads connecting the pen operating magnet to its controlling relay and source of energy are, in this case, very short and a relatively low voltage source of either alternating or direct current may be used for the pen operating magnet. The invention is not limited to this arrangement, however, and its advantages can be further realized by applying it to the transmission of pictures from a distance over telephone and telegraph wires or by radio signaling systems. In the latter case the relay 38 shown in Fig. 4 of the drawings could be made to control a high power radio transmitter using the full power of the transmitting station in so doing and the pen operating magnet 1 would be connected to receiving circuit at the distant receiving station. In this case, of course, the cylinders 16 and 20 would be widely separated and would necessarily be driven by separate sources of power. It would be necessary then to maintain the cylinders in synchronism. Means for so doing are well known in the art, however, and do not form part of the present invention.

It will further be recognized that the rotating cylinders shown for transmitting and receiving the picture are not essential to the invention. Any other means for causing a beam of light to successively traverse the entire surface of a picture to be reproduced could be used equally well. Where pictures are to be reproduced by printing processes it may be advantageous to record them on flat plates instead of cylinders and such a system is obviously within the scope of the invention.

Furthermore, while I have described my invention as applied to the well known etching and half tone engraving processes, it will be obvious to those skilled in the art that it is equally well adapted to other methods of reproducing records, as, for example, lithographing or mimeographing. In the case of the former, the paraffin record of the picture can be placed directly on absorbent paper on which the paraffin will make a greasy coating. The paper can then be moistened and inked whereupon the ink will adhere only to the paraffin covering and not to the wet paper and prints may be made in the usual manner. In the mimeographing process the paraffin image can be placed on Japanese tis-

sue which can thereafter be used directly for mimeographing as the mimeograph ink will be forced through the tissue but not through the paraffin.

It should be noted that in all of these processes it will be necessary to arrange the receiving machine for the particular process which is used, for example, in the zinc or copper etching process the picture must be reversed left to right as it is applied to the plate so that when it is printed from the plate the print will correspond exactly to the original. This can be arranged by properly choosing the relative direction of motion of the transmitting and receiving cylinders. In the mimeographed process it will be necessary to place a negative on the tissue rather than a positive but this can be taken care of by modifying the circuit arrangements in Fig. 4 as fully explained in my copending application 695,175 to send dots closely spaced for the light portions of the picture and dots with increased spacing for the dark portions.

Claims:

1. The method of reproducing prints of graphical records which consists in translating the record into varying electric currents and recording the current variations on a printing medium by depositing thereon acid resisting material in accordance with said varying currents.

2. The method of reproducing prints of graphical records which consists in progressively translating small areas of the record into varying electric currents and recording the current variations on a printing medium by depositing thereon acid resisting material in accordance with said varying currents.

3. The method of reproducing prints of graphical records which consists in translating the record into varying electric currents and recording the current variations on metal by depositing thereon acid resisting material in accordance with said varying currents.

4. The method of reproducing prints of graphical records which consists in progressively translating small areas of the record into varying electric currents and recording the current variations on metal by depositing thereon acid resisting material in accordance with said varying currents.

5. The method of forming plates for printing reproductions of graphical records which consists in progressively translating small areas of the record into varying electric currents, recording the current variations on metal by depositing thereon acid resisting material in accordance with said varying currents and thereafter etching the metal.

6. The method of forming plates for printing reproductions of graphical records which consists in progressively translating

small areas of the record into electric currents varying according to the light intensity of the areas, recording the current variations on metal by depositing thereon acid resisting material in accordance with said varying currents and etching the metal with successive acid bites.

7. The method of forming plates for printing reproductions of graphical records which consists in progressively modifying a light ray in accordance with the light intensity of small areas of the record, translating the variations of the light ray into varying electric currents, recording the current variations on metal by depositing thereon acid resisting material in accordance with said varying currents and thereafter etching the metal.

8. The method of forming plates for reproducing prints of graphical records transmitted by signaling impulses which consists in recording the impulses on metal by depositing thereon an acid resisting material in accordance with said varying currents and thereafter etching the metal.

9. The method of forming plates for reproducing prints of graphical records transmitted by signaling impulses which consists in recording the impulses on metal by depositing thereon an acid resisting material in accordance with said varying currents and thereafter subjecting the metal to successive acid bites.

10. In an apparatus for reproducing graphical records, means for translating small areas of the said record into varying electric currents, a metallic surface, and means controlled by said translating means for depositing an acid resisting material upon said metallic surface, said material being deposited in proportion to the pigmentation of the said graphical record.

11. In an apparatus for reproducing graphical records, means for translating small areas of the said record into varying electric currents, a metallic surface, and a pen controlled by said translating means for depositing an acid resisting material upon said metallic surface, said material being deposited in proportion to the pigmentation of the said graphical record.

12. In an apparatus for reproducing graphical records, means for translating small areas of the said record into varying electric currents, a metallic surface, a pen for depositing an acid resisting material upon said metallic surface, and an electromagnet for controlling the operation of said pen, said magnet being energized to actuate said pen in proportion to the varying electric currents in said translating means, whereby the produced record is similar to the original graphical record.

13. In an apparatus for reproducing graphical records, means for translating

small areas of the said record into varying electric currents, a metallic surface, a pen for depositing an acid resisting material upon said metallic surface, a tank containing said acid resisting material associated with said pen, and an electromagnet for controlling the operation of said pen, said magnet being energized to actuate said pen in proportion to the varying electric currents in said translating means, whereby the produced record is similar to the original graphical record.

14. In an apparatus for reproducing graphical records, means for translating small areas of the said record into varying electric currents, a metallic surface, a pen for depositing an acid resisting material upon said metallic surface, a tank containing said acid resisting material associated with said pen, means for keeping said acid resisting material in a liquid state, and an electromagnet for controlling the operation of said pen, said magnet being energized to actuate said pen in proportion to the varying electric currents in said translating means, whereby the produced record is similar to the original graphical record.

15. In an apparatus for reproducing graphical records, means for translating small areas of the said record into varying electric currents, a metallic surface, a pen for depositing an acid resisting material upon said metallic surface, a tank containing said acid resisting material associated with said pen, means for keeping said acid resisting material in a liquid state, a wick connecting said pen with said liquid acid resisting material, and means operable from said translating means for causing said pen to deposit said material upon said surface.

16. The method of reproducing prints of graphical records which consists in translating the record into varying electrical currents and recording the current variations on a surface by depositing thereon a waxy fluid in accordance with said varying currents.

17. In an apparatus for reproducing graphical records, means for translating small areas of the said records into varying electric currents, a recording surface, a tank containing a waxy recording substance, means for maintaining said waxy substance at a temperature above the melting point to keep said wax in a liquid state, a pen for depositing said waxy substance in its liquefied state upon said recording surface, a tube connecting said pen with said liquefied waxy substance in said tank, and means operable from said translating means for causing said pen to deposit said waxy material on said recording surface in accordance with the variations in said electric currents

RICHARD H. RANGER.
